UNITED STATES PATENT OFFICE.

THOMAS R. KENNEDY AND EDWARD J. KING, OF ROCHESTER, NEW YORK, ASSIGNORS TO THE CO-OPERATIVE FOUNDRY COMPANY, OF SAME PLACE.

DESIGN FOR A STOVE.

SPECIFICATION forming part of Design No. 31,605, dated October 3, 1899.

Application filed September 12, 1899. Serial No. 730,271. Term of patent 7 years.

To all whom it may concern:

Be it known that we, THOMAS R. KENNEDY and EDWARD J. KING, citizens of the United States, residing at Rochester, Monroe county, State of New York, have invented and produced a new and original Design for a Stove, of which the following is a specification, reference being had to the accompanying drawing, forming a part thereof.

10 The drawing is a perspective view of a stove, showing our design.

The leading or material feature of our design is the configuration of the stove and the ornamentation thereon.

15 The base A of the stove is provided with the scroll ornamentation extending down upon the legs, as shown, and at the top with a band B of rounding corrugations.

20 The body C of the stove is substantially rectangular, being provided at the lower central portion with the medallion D, the scroll and leaf ornamentation at the sides extending toward the center, the ornamental brack-

ets E, and the ornamental rail F. At or near the center of the front of the body is the ornamental panel G, and at the sides is provided the leaf and scroll ornamentation H, which extends upwardly at the corners to the rim of the top section I. At the sides of the body are the panels or doors J, having the rounded edges and ornamented as shown. ²⁵

I indicates the top section, having the band *i* at its lower edge and rounded and ornamented as shown.

K indicates the top lid or section, ornamented as shown and surmounted by an ornamental urn M. ³⁵

We claim—

The design for a stove substantially as herein shown and described.

THOMAS R. KENNEDY.
EDWARD J. KING.
